J. T. FOSTER.

Potato Digger.

No. 9,069.

Patented June 29, 1852.

UNITED STATES PATENT OFFICE.

JOHN T. FOSTER, OF NEW YORK, N. Y.

IMPROVEMENT IN POTATO-DIGGERS AND STONE-GATHERERS.

Specification forming part of Letters Patent No. 9,069, dated June 29, 1852.

To all whom it may concern:

Be it known that I, JOHN T. FOSTER, of the city, county, and State of New York, have invented a new and Improved Machine for Gathering Stones or other Substances or Articles, as Potatoes, Fruits, &c.; and I do hereby declare the following to be a full description of the same.

The nature of my invention consists in placing on the axis of a set of cart-wheels a roller having a series of rows of pins, of suitable lengths for the purpose required, secured in its periphery, and combining with the same an apron having a series of teeth in it for raking or gathering the stones or other articles as it is being dragged over the surface of the ground, and also a discharging trough or plate having a series of teeth attached to it, and projecting between the pins over on the top of the roller, so that as the stones or other articles are gathered or raked up by the teeth of the apron and carried up by the pins on the roller they are discharged on the teeth of the discharger trough or plate to fall into the box for containing them.

To describe my invention more particularly, I will refer to the annexed drawings, forming a part of this schedule, the same letters referring to the same parts wherever they occur.

Figure 1 is a plan view of the machine. Fig. 2 is a side elevation of the same, having one of the wheels removed from the axle-tree to exhibit the roller, apron, and discharging-plate. Fig. 3 is a plan view of the apron-roller and discharging-plate.

Letters A A are the wheels of a cart, arranged on an axle-tree, B. Letter C is the frame of the cart and shafts attached thereto. To the side of this frame is a box, D, into which the stones, potatoes, or other article is deposited. The position of this box is not material, as it may be placed between the shafts or other part of the cart-frame to the same advantage, and therefore its arrangement is not deemed essential so long as the object is attained by having the box in any convenient place for collecting the stones, &c., picked up.

Letter E is a roller secured on the axle-tree of the cart-wheels, having a series of rows of pins secured in its periphery. This roller may be made of wood or metal, or of wood cored with metal, and of any size required for the uses to which it is applied.

F F, &c., are the series of rows of pins, which are made of wood or metal some six to twelve inches (more or less) in length, and set in four or more rows lengthwise across the rollers, and two to four (more or less) inches apart. The object of these pins is to carry up the stone or other article that is raked or picked up by the teeth of the apron G, surrounding the back part of the roller. This apron is of iron, having a series of teeth, g' g' g', &c., at its lower edge for the purpose of raking or picking up the stones, potatoes, &c., from the ground as the machine is carried forward.

H H are two ear-pieces attached to the back of the apron for securing it in position between the frame of the cart. This apron is intended to be made adjustable by means of the ear-pieces or other suitable contrivance for the purpose of regulating the dip of the teeth, so as to adapt it to the various uses of a stone or potato gatherer, or other purposes to which it may be applied.

Letter I is the discharger trough or bed, having an outlet to the box D for the deposit of the stones, &c. Attached to this trough are a series of teeth, J J, &c., passing between the pins on the roller, and extending over and on it to near its highest point, so that as the stone or other article is carried over the roller by the pins it readily rolls on the ends of the teeth, and as the pins recede between the teeth allows it to fall down the lateral downward inclination of the teeth on the bed of the trough and so to the deposit-box. As the points of the teeth J are liable to get blunted or bent up, it is intended, should it be required, to cut grooves or channel-ways round the periphery of the roller for them to run in, so as to be level with the surface of the roller. It is also presumed that the mode of discharging the stones or potatoes, &c., may be varied as to position and inclination, and direction of the mode of discharging, and therefore I desire it to be distinctly understood that I do not limit myself to this precise detail of my invention, but consider my invention to consist in the use of any analogous devices for the purposes described.

Having now described my invention, I will explain its operations:

When the machine is put in operation, the teeth of the apron being set so as to take up the stones and the cart moved forward, they

are gathered on the points of them, as seen in Fig. 2, and by the action of the pins on the roller as it comes round are lifted up on the points of them between the apron till by their gravitation they fall on the face of the roller at the top, and by means of sides to the roller, should it be necessary to use them, are carried over and on the ends of the teeth J J, which, passing up between the pins, and having an inclination backward and downward, allow the article or substance to fall into the deposit box as soon as the pins pass down to the under side of the roller to carry up again in like manner a second load.

Having now set forth the nature of my in-

vention, I will proceed to state what I claim and desire to secure by Letters Patent—

The use of the roller E, having a series of rows of pins in its periphery, and secured on an axle-tree of a cart or other moving apparatus, in combination with an adjustable apron, G, having teeth in it, and a discharging-plate, J, having teeth in it, substantially for the purpose of gathering stones, potatoes, fruit, or other substances or articles and depositing them in a box, as hereinbefore set forth.

J. T. FOSTER.
